[57] ABSTRACT

The present invention relates to new pharmacologically valuable ketone derivatives exhibiting a distinct dilatory action on the cerebral vessels and which have the general formula

and their pharmaceutically acceptable acid addition salts, wherein

R₁ stands for a member selected from the group consisting of —CN, —CONH₂, —COOH, —COONa and —COOK,

R₂ stands for a member selected from the group consisting of

and

X stands for alkylene having 1 to 4 carbon atoms,

Y stands for a member selected from the group consisting of —O—CO— and —CO—NH—,

R₃ and R₄ each stand for a member selected from the group consisting of hydrogen and alkyl having 1 to 6 carbon atoms,

R₅ stands for a member selected from the group consisting of hydrogen and —OH,

the nucleus I may have 1 to 3 alkoxy, halogen, alkyl or nitro substituents,

the nucleus II may have 1 to 3 alkoxy, halogen or alkyl substituents

the nucleus III may be substituted by 1 to 3 methoxy groups and to processes for producing said ketone derivatives.

ALPHA-(N-BENZOYLOXY AND PHENYLAMINO
ALKYL-PIPERAZINO)-BETA-BENZOYL-
PROPIONIC ACID DERIVATIVES

This application is a division of application Ser. No. 5
239,359, filed Mar. 29, 1972.

The present invention relates to new, pharmacologically valuable ketone derivatives of the general formula

I

wherein

R_1 stands for CN, CONH₂, COOH, COONa or
COOK,
 R_2 stands for

or

X stands for alkylene having 1 to 4 carbon atoms,

Y stands for $-O-CO-$ or $-CO-NH-$

R_3 and R_4 , each stand for hydrogen or alkyl having up to 6 carbon atoms, and

R_5 stands for hydrogen or OH,

the nucleus I may have 1 to 3 alkoxy, halogen, alkyl or nitro substituents,

the nucleus II may have 1 to 3 alkoxy, halogen or alkyl substituents, and

the nucleus III may be substituted by 1 to 3 methoxy groups.

The symbols R_1 , R_2 , R_3 , R_4 , R_5 , X and Y used in the above formula have the same meanings throughout the specification, and nuclei indexed I, II or III may be substituted as defined above.

The compounds of general formula I contain at least one basic nitrogen atom and may consequently form or be formed as salts, in particular hydrohalides, and the invention extends to such acid addition salts, where pharmaceutically acceptable.

Preferred halogen substituents for the nucleus I and/or the nucleus II are fluorine, chlorine and bromine. Preferred alkyl substituents of the nucleus I and of the nucleus II contain 1 to 8 carbon atoms. Preferred alkoxyl substituents are methoxy groups.

The compounds of formula I may be prepared, for example, by the addition of amines of the general formula

to compounds of the general formula

III

Those compounds of formula I in which R_2 stands for

and Y represents the $-O-CO$ group, so that they have the general formula

IV

15

may also be synthesized by the addition of amines having the general formula

V

to compounds of the general formula III followed by 25 esterification of the adducts with benzoic acid derivatives of the general formula

VI

30

wherein Z stands for a halogen atom or the radical

VII

Those compounds of formula I in which R_1 stands for 40 a nitrile group may also be prepared by addition of HCN to vinyllogous amines of the general formula

VII

45

Those compounds of formula I in which R_1 stands for 50 a COOH, COONa or COOK group may also be prepared by acid saponification of the corresponding nitriles VIII according to the following reaction:

VIII

IX

or, in some cases, by diazotization of the corresponding 55 carbonamides X according to the following reaction equation:

X

60

XI

Wherein R_1 is COONa or COOK , the carboxyl group in compound IX is converted to the corresponding sodium or potassium carboxylate.

Such of the starting materials III as are not yet described in the literature may be prepared by known methods.

Thus, compounds of formula III, wherein R_1 represents the nitrile group, may be prepared by a method analogous to that described by A. Nesmeyanov (Dokl. Akad. Nauk SSSR, 115, page 315 (1957)), by reacting compounds of the general formula

with trimethylamine and subsequent reaction with KCN :

The chlorides XI necessary for this purpose may be prepared, as far as they are not yet described in literature, according to known *per se* methods. The simplest method for the preparation of the chlorides XI consists in the addition, in the presence of Friedel-Crafts-type catalysts, of suitable acid chlorides XV on acetylene according to the following reaction equation:

In the case of certain acid chlorides this reaction is difficult to carry out, for instance if the nucleus I bears one or more alkoxy groups. In this case the corresponding acetophenones XVI are subjected to an alkaline ester condensation with formiates. From the sodium or potassium salts XVII of the benzoylvinylalcohols thus obtained it is possible to prepare by way of hydrolysis the benzoylvinylalcohols XVIII which on their part may be converted with suitable chlorinating agents, such as thionylchloride or phosphortrichloride, to the benzoylvinylchlorides XI:

Initial compounds of formula III wherein R_1 represents the CO-NH_2 group may be prepared by partial saponification of the corresponding nitriles, for in-

stance with concentrated sulfuric acid according to the following reaction scheme:

Initial compounds of formula III wherein R_1 represents the COOH group may be prepared either by diazotization of the corresponding carbonamides XX according to the following reaction scheme

or directly by saponification of the nitriles XIX according to the following scheme

or by reaction of maleic acid anhydride with the corresponding benzene derivatives under the conditions of the Freidel-Crafts reaction

The compounds of general formula I of the present invention are valuable pharmaceuticals. They exert, especially where R_1 means CN , for instance, a distinct dilatory action on the cerebral vessels and are, in this respect, far superior to other known substances of this kind. The compounds of the present invention and their pharmaceutically acceptable salts may be employed together with pharmaceutically acceptable diluents or carriers for the preparation of pharmaceutical formulations such as tablets, dragees, suppositories, capsules, solutions, suspensions or emulsions.

These pharmaceutical preparations may also contain other therapeutically active substances.

Pharmacological investigations of the dilatory action of compounds according to the invention on the cerebral vessels were carried out in anaesthetized dogs by observing the changes in blood flow and oxygen tension of the brain-surface. The dogs were anaesthetized with Urethane-Chloralose-Dial-Nembutal (250-15-10-4 mg./kg. i.v.). Over the left-hand hemisphere of the brain the skull and the dura mater were opened by circular incision with a diameter of 2 to 3 cms. A heat-conductive probe (Standard model P 1 of Messrs. Hartmann and Braun A.G., Frankfurt/Main) was applied to the brain under a slight pressure for local blood flow determinations in the cerebral cortex (Literature consulted:

K. GOLENHOFFEN, H. HENSEL, G. HILDEBRANDT: "Durchblutungsmessung mit Wärmeleitelmatten in Forschung und Klinik," Georg Thieme Verlag Stuttgart, 1963). Besides the heat-conductive probe, a teflon-coated multiwire-platinum electrode

supplied by Eschweiler of Kiel, was applied to the brain for measuring the local oxygen tension (Literature consulted: D.W. LUBBERS "Methods of measuring oxygen tensions of blood and organ surfaces" in D.P. PAYNE and D.W. HILL "Oxygen Measurements in Blood and Tissues and their Significance" J. and A. Churchill Ltd., London 1966)). Blood pressure was measured in the femoral artery with the aid of an elec-
tromanometer of the STATHAM straingauge type.

The following table gives the results of the above 10 pharmacological investigations.

6
EXAMPLE 1

2.87 g. p-chlorobenzoylacrylonitrile (formula: $\text{Cl}-\text{C}_6\text{H}_5-\text{CO}-\text{CH}=\text{CH}-\text{C}=\text{N}$) are dissolved in 30 c.c. 5 dioxane, 2.27 g. norephedrin are added, the reaction mixture is completely dissolved with gentle heating and then allowed to stand for 48 hours at room temperature. Subsequently, it is concentrated in vacuo. The residue obtained is a dark colored oil which solidifies by the addition of petroleum ether. It is then sucked off, dried and triturated several times with warm water.

The following examples are given for the purpose of a better understanding of the nature and the objects of this invention. The temperatures are given in degrees Centigrade.

The water-insoluble part is separated, dried, recrystallized once from benzene/petroleum ether and converted with ethanolic hydrochloric acid and with the concurrent use of anhydrous ether to the hydrochlo-

ride. The hydrochloride is reconverted in the usual manner to the base. After recrystallization from benzene/petroleum ether one obtains the 3-(p-chlorobenzoyl)-2-(α -methyl- β -hydroxy-phenethylamino)-propionitrile having a melting point of 112–114°.

Analysis: (C₁₆H₁₆Cl₁N₂O₂)

calculated: C 66.6 H 5.6 N 8.2
found: 66.3 5.5 8.0
Yield: 2.9 g. = 56.5% of the theoretical

The p-chlorobenzoylacrylonitrile required as starting material may be prepared as follows:

A solution consisting of 14 g. p-chlorobenzoylvinylchloride in 105 c.c. anhydrous acetone in admixed with stirring at –35° with 7 c.c. trimethylamine. While stirring, the solution is allowed to reach room temperature, then the reaction mixture is sucked off from the separated precipitate and washed with anhydrous acetone. The dry product is then suspended in 90 c.c. benzene, a solution consisting of 3.8 g. trimethylammonium chloride in 4 c.c. water is added and a further solution consisting of 7 g. KCH in 36 c.c. water is added dropwise while cooling with ice and stirring. The reaction mixture is then heated to room temperature, stirred for another 15 hours, the benzene phase is separated and the aqueous phase is extracted twice with benzene. The combined benzene phases are washed once with water, dried with Na₂SO₄ and concentrated in vacuo. By recrystallization of the muddy residue from ligroin one obtains the p-chlorobenzoylacrylonitrile having a melting point of 144°–146°.

Analysis: (C₁₆H₁₆Cl₁N₁O₁)

calculated: C 62.6 H 3.1 N 7.3
found: 63.0 3.5 7.2
Yield: 7.9 g. = 59.4% of the theoretical

Analogously to the description given hereinbefore it is possible to prepare, for instance, the following benzoylacrylonitriles:

	Chemical Structure	CO-CH=CH-C≡N	Melting point (degrees)	Boiling point
			83–85	
			92	
			30	
			85	
			145°/2 mm.	
			105	
			145	
			141	
			128	

The p-chlorobenzoylvinylchloride required for the preparation of p-chlorobenzoylacrylonitrile may be obtained with good yields according to N. Kochetkov (Zh. Obsch. Khim. 26, page 595 (1956)) by addition of p-chlorobenzoylchloride on acetylene. Analogously, for instance, the following vinylchlorides may be prepared.

	Chemical Structure I	Melting point (degrees)	Boiling point
		94°/2 mm.	
		119–123°/2 mm.	
		74	
		107–111°/2 mm.	
		112–118°/1 mm.	
		178–185°/1.5 mm.	
10		94	

EXAMPLE 2

15 3.09 g. 2-[piperazinyl(1)]-acetic acid-3',4',5'-trimethoxyanilide are dissolved in 50 c.c. dioxane, 2.66 g. 2',3',4'-trimethoxybenzoylacrylic acid are added and the mixture is stirred for 30 hours at 70°. The separated precipitate is sucked off, washed first with dioxane, then thoroughly with water, dried and finally boiled with 75 c.c. alcohol. The residue thus obtained is the 3-[2',3',4'-trimethoxybenzoyl]-2-[4-(3',4',5'-trimethoxyanilino)-oxoethyl-piperazinyl(1)-propionic acid.

25

Melting point: 169°
Analysis: (C₂₈H₃₇N₃O₁₀)
calculated: C 58.4 H 6.4 N 7.3
30 found 58.1 6.4 7.4
Yield: 3 g. = 52% of the theoretical

The same product is obtained by treating N-[2-35 (2',3',4'-trimethoxybenzoyl)-1-cyanoethyl]-N'-(acet-3',4',5'-trimethoxy-anilido)-piperazine-hydrochloride (prepared by addition of 2-[piperazinyl (1)]-acetic acid-3',4',5'-trimethoxyanilide on 2',3',4'-trimethoxybenzoylacrylonitrile analogously to the prescription of Example 5, melting point: 181°) with concentrated sulfuric acid. The acid may be converted with an equimolar amount of sodium ethylate to its sodium salt.
Melting point: >250° dec.

45 The 2',3',4'-trimethoxybenzoylacrylic acid required as starting material may be prepared as follows:

4.5 g. 2',3',4'-trimethoxybenzoyl-acrylic acid amide are dissolved with stirring in 34 c.c. concentrated sulfuric acid. The mixture is cooled down to an internal temperature of –45°, 3.55 g. NaNO₂ are added and then 10 50 c.c. water are slowly added dropwise with stirring, whereby the temperature rises to –10°. Subsequently, a further 51 c.c. water are added dropwise in such a manner that finally the temperature reaches +3° and stirring is continued for another 90 minutes at room temperature. The reaction mixture is then sucked off, the residue is washed with water, dissolved in soda solution of 10%, filtered off from a slightly turbid mass and the filtrate is acidified with hydrochloric acid of 10%. Obtained is an oily precipitate which solidifies after a short while. The reaction product is sucked off, washed with water and dried, then dissolved with gentle heating in toluene and filtered off from a minor residue. The filtrate is admixed with petroleum ether and the separated precipitate is sucked off. Obtained is the 2',3',4'-trimethoxybenzoylacrylic acid.

60

65

Melting point: 89°-90°
Analysis: (C₁₃H₁₄O₈)

calculated: C 58.6 H 5.3 O 36.1
found: 58.7 5.2 37.2
Yield: 3.3 g. = 73% of the theoretical

The 2-[piperazinyl (1)-acetic acid-3',4',5'-trimethoxy-anilide which is also required as starting material may be prepared as follows:

18.3 g of 3,4,5-trimethoxyaniline and 10.1 g. triethylamine are dissolved in 300 c.c. anhydrous dioxane, 11.3 g. chloroacetylchloride are added at 15°-20° with stirring and the reaction mixture is stirred for 16 hours at room temperature. It is then sucked off from the separated triethylammonium chloride, the filtrate is evaporated in vacuo, the residue is treated with ether and sucked off.

Obtained are 23 g. N-chloroacetyl-3',4',5'-trimethoxy-aniline having a melting point of 103°.

A solution consisting of 27 g. piperazine in 100 c.c. isopropanol is admixed, while stirring at room temperature, with a solution consisting of 14 g. N-chloroacetyl-3',4',5'-trimethoxyaniline in 60 c.c. dioxane. The reaction solution is then heated for 7 hours under reflux, evaporated and the residue is dissolved in 2N sodium hydroxide solution and chloroform. The chloroform phase is separated, the aqueous phase is again extracted with CHCl₃, both chloroform extracts are combined, washed and concentrated in vacuo. The remaining oil solidifies by the addition of diisopropylether. Obtained are after suction-filtration 15 g. 2-[piperazinyl (1)-acetic acid-3',4',5'-trimethoxyanilide having a melting point of 125°.

EXAMPLE 3

2 g. 3'-methoxybenzoylacrylonitrile are dissolved in 30 c.c. dioxane, 1.39 g. N-hydroxyethylpiperazine are added and the solution is first allowed to stand for one hour at room temperature and then concentrated in vacuo. The residue is recrystallized from benzene/petroleum ether. Obtained are 3.2 g. N-[2-(m-methoxybenzoyl)-1-cyano-ethyl]-N'-(hydroxyethyl)-piperazine having a melting point of 126°-128°.

3.2 g. of the hydroxyethylpiperazine are dissolved in 40 c.c. dioxane, 1.03 g. triethylamine are added and, at room temperature, a solution consisting of 2.33 g. 3,4-,5-trimethoxybenzoylchloride in 15 c.c. dioxane is added dropwise while stirring. Subsequently, the reaction mixture is stirred for another 16 hours at room temperature. A further 0.54 g. triethylamine as well as a solution consisting of 1.14 g. 3,4,5-trimethoxybenzoylchloride in dioxane are added and this mixture is again stirred for 16 hours at room temperature. After sucking off, the filtrate is concentrated in vacuo, the residue is dissolved in ethanolic hydrochloric acid and admixed with ether. The precipitate obtained is a slightly muddy hydrochloride. After conversion to the base and subsequent reconversion to the hydrochloride one obtains the N-[2-(m-methoxybenzoyl-1-cyanoethyl)-N'-(3',4',5'-trimethoxybenzoyloxyethyl)-piperazine-dihydrochloride in the form of crystals melting at 146°.

Analysis: (C₂₇H₃₅Cl₂N₃O₇)

calculated: C 55.5 H 6.0 N 7.2
found: 55.0 6.1 7.1
Yield: 2.9 g. = 53% of the theoretical

The 3'-methoxybenzoylacrylonitrile required as starting material may be prepared analogously to the description given in Example 1 from 3'-methoxybenzoylvinylchloride. The 3'-methoxybenzoylvinylchloride required for this purpose may be prepared as follows:

A solution consisting of 17.8 g. ethyl formate and 30 g. 3-methoxyacetophenone is added dropwise, while stirring at 8°-10°, to a suspension of 13 g. sodium methylate in 100 c.c. anhydrous benzene. Stirring is continued for another 16 hours at room temperature, then the reaction mixture is sucked off, washed with anhydrous alcohol and the residue is dried in vacuo. Obtained are 38.9 g. of the sodium salt of the 3'-methoxybenzoylvinyl alcohol.

24.2 g. of the sodium salt are suspended in 80 c.c. benzene. Subsequently, 100 c.c. water and 60 c.c. sulfuric acid of 10% are added and the mixture is vigorously stirred. When it is completely dissolved, the benzene layer is separated and the aqueous phase is extracted twice with benzene.

The combined benzene extracts are then gently heated under reflux with 15.4 g. thionylchloride, the excess thionyl chloride and the benzene are then distilled off in vacuo and the residue is fractionated in vacuo.

Obtained is the 3'-methoxybenzoylvinylchloride.

35

Boiling point: 150°/3-4 mm.
Analysis: (C₁₀H₉ClO₂)

calculated: C 61.0 H 4.5
found: 60.7 4.5
Yield: 16.2 g. = 38% of the theoretical

Analogously, the following methoxylated benzoylvinylchlorides may be prepared from the corresponding acetophenones via the sodium salts of the benzoylvinylalcohols:

		Melting point (degrees)	Boiling point
2,3,4-(CH ₃ O) ₃ C ₆ H ₂			108-171°/1-2 mm.
4-CH ₃ O-C ₆ H ₄			156-159°/3 mm.
4-CH ₃ O-2,3-Cl ₂ C ₆ H ₂	72-74		
3,4,5-(CH ₃ O) ₃ C ₆ H ₂		180°/1 mm.	
2,4,6-(CH ₃ O) ₃ C ₆ H ₂	78-80		

EXAMPLE 4

2 g. 2',3',4'-trimethoxybenzoylacrylamide are dissolved in 40 c.c. dioxane, 1.14 g. norephedrin are added and the mixture is stirred for 20 hours at room temperature, then heated during one hour at 80° and the solution is concentrated in vacuo. The remaining oil solidifies when it is treated with ether. The residue is sucked off, washed with ether, then dissolved in warmed ethyl acetate and the filtrate is admixed with

65

petroleum ether whereby a precipitate is formed which crystallizes after a short while. It is sucked off and the residue is washed with petroleum ether.

Thus obtained is the N-[2-(2',3',4'-trimethoxybenzoyl)-1-carbonamido-ethyl]-norephedrin.

Melting point: 105°
Analysis: (C₂₂H₂₈N₂O₆)

calculated: C 63.5 H 6.7 N 6.7 O 23.1
found: 63.4 7.1 6.4 23.5
Yield: 2.1 g. = 67% of the theoretical

The 2',3',4'-trimethoxybenzoyl acrylic acid amide required as starting material may be prepared as follows:

8 g. 2',3',4'-trimethoxybenzoyl acrylonitrile are dissolved in 40 c.c. concentrated sulfuric acid and heated in a water bath to an internal temperature of 75°. At this temperature, the mixture is allowed to stand for 3 minutes, then cooled and poured onto about 120 g. ice. The precipitated residue is sucked off and washed twice with little iced water. By recrystallization of the residue from water and with the concurrent use of little methanol one obtains the 2',3',4'-trimethoxybenzoyl acrylic acid amide.

Melting point: 150°-152°
Analysis: (C₁₃H₁₃NO₃)

calculated: C 58.9 H 5.7 N 5.3
found: 58.2 5.5 5.2
Yield: 6.5 g. = 76% of the theoretical

EXAMPLE 5

8.8 g. 3',4',5'-trimethoxybenzoyl acrylonitrile and 11 g. 2-[piperazinyl (1)-acetic acid-3',4',5'-trimethoxyanilide are stirred for 7 hours at 70° in 120 c.c. dioxane. The solution is then cooled down to room temperature, filtered off from residual parts, if any, and the filtrate is evaporated in vacuo. The oily residue is dissolved in little anhydrous dioxane, admixed with etheric hydrochloric acid, and the precipitate is sucked off and washed several times with ether. Subsequently, it is treated with water, whereby first muddy mass is formed which solidifies while further standing. The solid product is sucked off, suspended in dilute soda solution and immediately extracted three times with chloroform. The chloroform solution is washed with water, dried and concentrated in vacuo. The resinous residue is dissolved in anhydrous dioxane, admixed with etheric hydrochloric acid and the separated precipitate is sucked off and washed with ether. The residue is then stirred for one hour in about 30 c.c. water, whereby first a muddy mass is again formed which solidifies after a short while. After sucking off and recrystallizing from alcohol, one obtains the N-[2-(3',4',5'-trimethoxybenzoyl)-1-cyanoethyl]-N'-(acet-3',4',5'-trimethoxyanilido)-piperazine-hydrochloride.

Melting point: 178°
Analysis: (C₂₈H₃₇Cl₁N₄O₈)

calculated: C 56.7 H 6.2 Cl 6.0 N 9.4
found: 56.8 6.4 5.8 9.6

Analogously to the description given in Examples 1-5 the following compounds of the present invention may be obtained:

			Melting point (degrees)
2,3,4-(CH ₃ O) ₃ C ₆ H ₂	CN		140
2,3,4-(CH ₃ O) ₃ C ₆ H ₂	CONH ₂		187

¹ Dihydrochloride.² Hydrochloride.³ Dec.

What we claim is:

1. A compound of the formula

wherein Z stands for a member selected from the group consisting of $-\text{OH}$, $-\text{NH}_2$ and $-\text{ONa}$, X stands for alkylene with 1 - 4 carbon atoms, Y stands for a member selected from the group consisting of $-\text{O}-\text{CO}-$ and $-\text{CO}-\text{NH}-$, the nucleus I being selected from the group consisting of phenyl and mono-, di- and trimethoxyphenyl, and nucleus II being selected from the group consisting of phenyl and mono-, di- and trimethoxyphenyl, and the pharmaceutically acceptable acid addition salts of said compounds.

2. Compound according to claim 1, wherein nucleus I is monomethoxyphenyl, Z is $-\text{OH}$, X is $-\text{C}_3\text{H}_6-$, Y is $-\text{O}-\text{CO}-$ and nucleus II is trimethoxyphenyl, and

the pharmaceutically acceptable addition salts of said compound.

3. Compound according to claim 1, wherein nucleus I is trimethoxyphenyl, Z is $-\text{NH}_2$, X is $-\text{C}_2\text{H}_4-$, Y is $-\text{O}-\text{CO}-$, nucleus II is trimethoxyphenyl, and the pharmaceutically acceptable addition salts of said compound.

4. Compound according to claim 1, wherein in nucleus I is trimethoxyphenyl, Z is $-\text{ONa}$, X is $-\text{C}_3\text{H}_6-$, Y is $-\text{O}-\text{CO}-$, nucleus II is trimethoxyphenyl, and the pharmaceutically acceptable addition salts of said compound.

5. Compound according to claim 1, wherein nucleus I is trimethoxyphenyl, Z is $-\text{OH}$, X is $-\text{CH}_2-$, Y is $-\text{CO}-\text{NH}-$, nucleus II is trimethoxyphenyl, and the pharmaceutically acceptable addition salts of said compound.
